ALEXANDER SYDNEY WESTON,

INVENTOR,

BY *Julian J. Wittal,*
his ATTORNEY

UNITED STATES PATENT OFFICE

102,461

DESIGN FOR A POLYGONAL CIGARETTE LIGHTER

Alexander Sydney Weston, New York, N. Y.

Application October 5, 1936, Serial No. 65,163

Term of patent 3½ years

To all whom it may concern:

Be it known that I, Alexander Sydney Weston, a citizen of the United States, residing at New York, county and State of New York, have invented a new, original, and ornamental Design for a Polygonal Cigarette Lighter, of which the following is a specification, reference being had to the accompanying drawing, forming a part thereof.

In the drawing:

Fig. 1 is a side elevation of a polygonal cigarette lighter showing my new design;

Fig. 2 is a plan view thereof.

I claim:

The ornamental design for a polygonal cigarette lighter as shown.

ALEXANDER SYDNEY WESTON.
